(57) **CLAIM**

The ornamental design for a cap, as shown and described.

DESCRIPTION

FIG. 1 is a top front right perspective view of a cap showing our new design;

FIG. 2 is a top view thereof;

FIG. 3 is a right side view thereof;

FIG. 4 is a left side view thereof;

FIG. 5 is a front view thereof;

FIG. 6 is a back view thereof;

FIG. 7 is a top front right perspective view of a cap of FIGS. 1-6 in an in-use, open position;

FIG. 8 is a top view thereof;

FIG. 9 is a right side view thereof;

FIG. 10 is a left side view thereof;

FIG. 11 is a front view thereof;

FIG. 12 is a back view thereof;

FIG. 13 is a top right perspective view of a cap showing a second embodiment of our new design;

FIG. 14 is a top view thereof;

FIG. 15 is a right side view thereof;

FIG. 16 is a left side view thereof;

FIG. 17 is a front view thereof;

FIG. 18 is a back view thereof;

FIG. 19 is a top right perspective view of a cap of FIGS. 13-18 in an in-use, open position;

FIG. 20 is a top view thereof;

FIG. 21 is a top right perspective view of a cap showing a third embodiment of our new design;

FIG. 22 is a top view thereof;

FIG. 23 is a right side view thereof;

FIG. 24 is a left side view thereof;

FIG. 25 is a front view thereof;

FIG. 26 is a back view thereof;

FIG. 27 is a top right perspective view of a cap of FIGS. 21-26 in an in-use, open position; and,

FIG. 28 is a top view thereof.

The uneven-length broken lines in the figures represent unclaimed boundaries of the claimed design. The remaining even-length broken lines depict environment only and form no part of the claimed design.

(57) **CLAIM**

The ornamental design for a cap, as shown and described.

DESCRIPTION

FIG. 1 is a top front right perspective view of a cap showing our new design;

FIG. 2 is a top view thereof;
FIG. 3 is a right side view thereof;
FIG. 4 is a left side view thereof;
FIG. 5 is a front view thereof;
FIG. 6 is a back view thereof;
FIG. 7 is a top front right perspective view of a cap of FIGS.
1-6 in an in-use, open position;
FIG. 8 is a top view thereof;
FIG. 9 is a right side view thereof;
FIG. 10 is a left side view thereof;
FIG. 11 is a front view thereof;
FIG. 12 is a back view thereof;
FIG. 13 is a top right perspective view of a cap showing a
second embodiment of our new design;
FIG. 14 is a top view thereof;
FIG. 15 is a right side view thereof;
FIG. 16 is a left side view thereof;
FIG. 17 is a front view thereof;
FIG. 18 is a back view thereof;
FIG. 19 is a top right perspective view of a cap of FIGS. 13-18
in an in-use, open position;
FIG. 20 is a top view thereof;
FIG. 21 is a top right perspective view of a cap showing a third
embodiment of our new design;
FIG. 22 is a top view thereof;
FIG. 23 is a right side view thereof;
FIG. 24 is a left side view thereof;
FIG. 25 is a front view thereof;
FIG. 26 is a back view thereof;
FIG. 27 is a top right perspective view of a cap of FIGS. 21-26
in an in-use, open position, and;
FIG. 28 is a top view thereof.

The uneven-length broken lines in the figures represent
unclaimed boundaries of the claimed design. The remaining
even-length broken lines depict environment only and form
no part of the claimed design.
